UNITED STATES PATENT OFFICE

139,801

DESIGN FOR A GAME BOARD

Landon Napoleon Cheek, Nashville, Tenn., assignor to R. Pete Schield, Nashville, Tenn.

Application October 5, 1943, Serial No. 111,272

Term of patent 14 years

(Cl. D34—5)

To all whom it may concern:

Be it known that I, Landon Napoleon Cheek, a citizen of the United States of America, residing at Nashville, county of Davidson and State of Tennessee, have invented a new, original, and ornamental Design for a Game Board, of which the following is a specification, reference being had to the accompanying drawing, forming a part thereof, wherein:

I claim:

The ornamental design for a game board, as shown.

LANDON NAPOLEON CHEEK.
